United States Patent Office

Des. 191,894
Patented Dec. 5, 1961

191,894

ASH TRAY

Justin Sturm, Sylvan Road, Westport, Conn.

Filed Mar. 30, 1960, Ser. No. 59,943

Term of patent 14 years

(Cl. D85—2)

The FIGURE is a perspective view of an ash tray, showing my new design.

I claim:

The ornamental design for an ash tray, substantially as shown.
